UNITED STATES PATENT OFFICE.

JOHN R. VOSBURGH, OF JOHNSTOWN, NEW YORK.

REPAIR PLUG FOR INNER TUBES.

Application filed February 7, 1923. Serial No. 617,503.

To all whom it may concern:

Be it known that I, JOHN R. VOSBURGH, a citizen of the United States, residing at Johnstown, in the county of Fulton and State of New York, have invented certain new and useful Improvements in Repair Plugs for Inner Tubes, of which the following is a specification, reference being had to the accompanying drawings.

This invention relates to repair plugs for closing holes or punctures in flexible tubing such as hose, pneumatic tire tubes, and the like, and an important object of the invention is to provide a device which is capable of use for closing punctures of different sizes and which, by the use of alternative parts, may be employed for closing rents such as formed by blowouts.

A further object of the invention is to provide a device of this character which in effect rivets itself upon the tube to which it is applied, providing a perfect airtight seal without relying upon the use of cement.

A further object of the invention is to provide a device of this character which lends itself readily to the operation of closing the puncture and in which there is no necessity for holding the device in adjusted positions while making applications of its several parts, as will be hereinafter described.

These and other objects I accomplish by the construction and arrangement shown in the accompanying drawings wherein for the purpose of illustration is shown a preferred embodiment of my invention and wherein like reference characters designate like parts throughout.

In the drawings,

Figures 1 to 4 inclusive are sectional views showing various steps in the installation of the plug and washers;

Figure 5 shows one manner of modifying the construction of the washers for use with rents or tears in the tube;

Figure 6 is a perspective of the plug; and

Figure 7 is a detail view showing one manner of employing the plug.

Referring now more particularly to the drawings, the plug proper, indicated at 10, is substantially mushroom-shaped, the head 11 and stem 12 thereof being integral and being formed of resilient material, preferably a good grade of rubber. The stem 12 at a point spaced from the under surface of

the head has formed thereon an enlargement 13, the face of which, adjacent the head 11, forms the shoulder 14. The upper surface of the enlargement 14 tapers, as at 15, to the normal size of the stem. Upon the outer end of the stem an enlargement 16 is provided, the purpose of which will presently appear. In conjunction with the plug I employ washers 17, each concavo-convex in form, and having a central aperture 18 for the reception of the stem. In the majority of instances these washers will be provided at the convex face thereof with an enlargement 19 on the bore and of a size sufficient to permit seating of the end of the enlargement 13, though in some instances it may be desirable to form the washer without this enlargement. In some forms, washers such as illustrated in Fig. 5 may be necessary. In this figure a substantially oval washer is provided which is concavo-convex in cross-section. These washers will be employed for closing rents and slits in the tubes and will be provided with a plurality of openings 18 for the reception of plugs.

In the use of the device, the plug 10 has attached thereto a string or similar retaining element 20 and is forced through the opening or puncture 21 of the tube T. A washer 17 is applied to the stem 12 by threading the same upon the retaining element 20 and is likewise forced through the opening 21. The retaining element is then employed to draw the stem through the opening until the shoulder 14 has passed therethrough and engages upon the opposite side of the tube from the washer 17 and head 11, as illustrated in Fig. 2.

A second washer 17 is then employed, this second washer being of that type having the enlargement 19 of the central opening 18 thereof. This washer is forced downwardly upon the enlargement and the stem 12 tensioned until that portion thereof between the head 11 and the enlargement 13 is stretched a sufficient distance to permit the seating of the second washer 17 about the stem between the head 11 and enlargement 13. The stem is then released and the enlargement seats in the enlarged opening of the washer when the stem may be cut off flush with the upper surface of the washer, the portion of the enlargement retained within the enlargement of the central opening forming in effect a rivet head maintaining the sections in assembled relation.

Where the opening 21 is sufficiently small the washer 17 between the head and tube may be dispensed with and the head 11 employed to close the opening, and where the opening is too large for a single circular washer 17, an irregularly-shaped washer such as previously described may be employed. It will be obvious that the tension applied by the stem between the enlargement and the head will be sufficient to force the washer 17 firmly into contact with the tube to seal the opening 21. If desired, cement may be employed in applying the plug, but in many instances this will not be necessary.

Many changes being possible in the specific construction and shaping of the washers hereinbefore described without in any manner departing from my invention I do not limit myself to such specific structure as hereinbefore set forth, except as hereinafter claimed.

What is claimed, is:

1. Means for sealing punctures in tubes and the like, comprising in combination a mushroom-shaped plug having an enlargement on the stem thereof provided with a shoulder facing the head, and an elastic washer adapted to surround the stem between the shoulder and the head at the opposite side of the tube being repaired from the head.
2. Means for sealing punctures in tubes and the like, comprising in combination a mushroom-shaped plug having an enlargement on the stem thereof provided with a shoulder facing the head, and an elastic washer adapted to surround the stem between the shoulder and the head at the opposite side of the tube being repaired from

the head, said washer being concavo-convex in form and being provided in the convex face thereof with a socket receiving the lower end of said enlargement.

3. Means for sealing punctures in tubes and the like, comprising in combination with a mushroom-shaped sealing plug having an enlargement formed upon the stem thereof and having a shoulder facing the head, a washer concavo-convex in form and having its convex face abutting the concave face of the head and its concave face adapted to abut the inner face of the tube to be repaired.

4. A sealing plug for use in closing punctures in tubes comprising a mushroom-shaped element formed of rubber and having an enlargement upon the stem thereof, having a shoulder facing the head and concavo-convex washers having their concave faces opposed mounted upon the stem intermediate the enlargement and the head and adapted to receive therebetween the tube to be repaired.

5. A sealing plug for use in closing punctures in tubes comprising a mushroom-shaped element formed of rubber and having an enlargement upon the stem thereof, having a shoulder facing the head and concavo-convex washers having their concave faces opposed mounted upon the stem intermediate the enlargement and the head and adapted to receive therebetween the tube to be repaired, the convex face of the washer remote from the head being provided with a socket receiving the lower end of said enlargement.

In testimony whereof I hereunto affix my signature.

JOHN R. VOSBURGH.
